UNITED STATES PATENT OFFICE.

JOHN W. MAILLOT, OF NORTH ATTLEBOROUGH, MASSACHUSETTS, ASSIGNOR
TO F. M. WHITING & CO., OF SAME PLACE.

DESIGN FOR A SPOON.

SPECIFICATION forming part of Design No. 22,318, dated April 4, 1893.

Application filed January 28, 1893. Serial No. 460,166. Term of patent 3½ years.

To all whom it may concern:

Be it known that I, JOHN W. MAILLOT, a citizen of the United States, residing at North Attleborough, in the county of Bristol, State of Massachusetts, have invented and produced a new and original Design for Spoons, Forks, and the Like, of which the following is a specification.

In the drawings:—Figure 1, is a front view of a spoon embodying my design, and Fig. 2, is a view of the back of the handle.

While I have shown the design as applied to a spoon handle, it will be understood that it may be used for other handles as well. The spoon is intended as a souvenir of the World's Fair, and the handle on the front face is made up of ornamental configuration forming in the surface of the spoon the letters "C" "H" "I"

"C" "A" "G" "O," interlaced and overlapping. Within the letter "C," any suitable inscription may be placed. Below the last letter "O" are a series of flutings 8, extending downwardly therefrom. On the rear face of the handle, the margin is the rear configuration of the series of letters, the interior surface being plain.

I claim—

The design for a spoon, substantially as herein shown and described.

In testimony whereof I affix my signature in presence of two witnesses.

JOHN W. MAILLOT.

Witnesses:

WM. F. BOYD,
WM. H. POND.
